UNITED STATES PATENT OFFICE

2,096,717

GARMENT HANGER

Frederick Hille, Los Angeles, Calif.

Application December 28, 1934, Serial No. 759,514
Renewed March 2, 1937

2 Claims. (Cl. 223—95)

This invention relates to garment hangers and is an improvement over the construction disclosed in my prior United States Patent No. 1,922,161 issued August 15, 1933.

5 The hanger of the above construction comprised a rigid supporting bar, a pair of tubular members slidably mounted thereon having upward turned ends adapted to be inserted in the waist band of a garment and springs associated therewith normally urging them outwardly on said supporting bar into engagement with the waist band of the garment.

10 While the hanger very effectively served its intended purpose (and was adjustable to a certain degree) it was found necessary to make them in different sizes in order to support all size garments.

15 It is therefore the object of the present invention to provide a garment hanger of the character referred to so constructed that it may be easily and quickly adjusted to the waist band of practically all size garments, thereby eliminating the necessity of supplying them to the trade in different sizes.

20 Other objects and advantages will be apparent from the following description, reference being had to the accompanying drawing in which:

25 Fig. 1 is a side elevation of the improved garment hanger.

30 Fig. 2 is a top view of the hanger taken in the direction indicated by the arrow 2 of Fig. 1.

Fig. 3 is a bottom view taken in the direction indicated by the arrow 3 of Fig. 1.

35 Fig. 4 is a longitudinal section taken on line 4—4 of Fig. 2.

Fig. 5 is a detail section, lines 5—5 of Figs. 1 and 4.

Fig. 6 is a similar view to Fig. 5 but showing the spring latch in disengaged position.

40 Referring more specifically to the drawing 10 designates the supporting bar or member of the improved hanger which is preferably formed of round wire stock of sufficiently large diameter to render the same rigid.

45 Formed in bar 10 midway of its ends is an arched portion 11 and secured thereto is a hook 12 for supporting the hanger, in the usual manner.

Slidably and telescopically engaging the straight portions 13 of the bar are tubes 14 having 50 closed outer ends 15 and formed in the underside of said tubes are elongated slots 16 that receive pins or keys 17 projecting from the bars adjacent each end thereof.

Pins 17 serve to hold tubes 14 against rotation 55 on the straight portions 13 also to prevent sepa-

ration of them from the bar.

Disposed within each tube 14 is an expansion coil spring 18 the opposite ends of which engage respectively the closed ends 15 of said tubes and the end faces of the straight portion 13 of the bar. 5

Springs 18 normally urge the tubes outwardly on the bar and are partly under compression when mounted therein, outward movement of said tubes being limited by engagement of pins 17 with the ends of the slots 16. 10

Slidably and adjustably mounted on tubes 14 are tubular members 20 having upwardly turned ends 21 that are adapted to engage inside of the waist band of a garment not shown.

The present invention resides more specifically 15 in means for adjusting members 20 on the tubes 14 and retaining them in adjusted position whereby the distance between the upwardly turned ends 21 may be varied according to opening of the waist band of the garment to which the 20 hanger is to be applied, arranged as follows:

Formed in the upper side of tubes 14 is a plurality of evenly spaced cross slots designated at 22 that are adapted to be selectively brought into register with single slots 23 formed in the members 20 adjacent their inner ends. 25

Secured to members 20 by rivets or the like 24 are leaf springs 25 the free ends 26 of which normally extend through the slots formed in said members and tubes. 30

By turning the members 20 in relation to the tubes i. e. about one-half turn as shown in Fig. 6 the free ends of the springs will be moved out of register with the slots in the tubes thereby permitting members to be moved longitudinally 35 thereon whereby the springs may be selectively brought into engagement with any of the slots in the tubes thereby increasing or diminishing the distances between the upturned ends 21 for the purpose above referred to. 40

I claim:

1. A hanger of the character described comprising a supporting bar, tubes having a plurality of cross slots formed therein slidably mounted on each end of said supporting bar, springs normally 45 urging said tubes outwardly on said bar, tubular members slidably mounted on said tubes each having a slot therein adapted to be selectively brought into register with the slots in said tubes, and leaf springs secured to said tubular members 50 and arranged to extend through the slots formed therein and the slots in the tubes whereby said tubular members may be adjusted longitudinally on said tubes and retained in adjusted position thereon. 55

2. A hanger of the character described comprising a supporting bar, tubes having outer closed ends and longitudinal slots therein slidably mounted on each end of said supporting bar, expansion coil springs disposed in said tubes and normally urging them outwardly, pins secured to said supporting bar and projecting into the longitudinal slots in said tubes for preventing rotation of and limiting outward movement of
5 the same thereon, said tubes having a plurality of crosswise slots formed therein with the bottom
10

faces thereof lying in a plane tangentially to the outer face of said supporting bar, tubular members slidably and rotatably mounted on said tubes and having crosswise slots therein, and leaf springs secured at one end to said tubular members and having flattened free ends normally extending through the slots therein and the slots in said tubes whereby said tubular members may be adjusted longitudinally on said tubes.

FRED HILLE. 10
